UNITED STATES PATENT OFFICE.

FRANK A. SNOW, OF DAVID CITY, NEBRASKA.

STOVE-PIPE FASTENER.

SPECIFICATION forming part of Letters Patent No. 447,168, dated February 24, 1891.

Application filed April 9, 1890. Serial No. 347,223. (No model.)

To all whom it may concern:

Be it known that I, FRANK A. SNOW, of David City, in the county of Butler and State of Nebraska, have invented a new and Improved Stove-Pipe Fastener, of which the following is a full, clear, and exact description.

My invention relates to improvements in stove-pipe fasteners; and the object of my invention is to provide a simple and efficient device by means of which a stove-pipe may be quickly and firmly secured in a wall or chimney-flue.

To this end the invention consists in certain features of construction and combinations of parts, which will be hereinafter fully described, and then pointed out in the claims.

Reference is to be had to the accompanying drawings, forming a part of this specification, in which similar letters of reference indicate corresponding parts in all the views.

Figure 1 is a side elevation of the device as applied to a stove-pipe and chimney-flue, the chimney and stove-pipe being shown in vertical section. Fig. 2 is a perspective view of the device. Fig. 3 is a detail view showing the manner in which the thumb-screw is applied to the pipe and fastener; and Fig. 4 is a side elevation of the device as applied to a stove-pipe and a thin wall, the stove-pipe being indicated by dotted lines.

The device consists of two members A and A', the member A being somewhat longer than the thickest wall to which the device will be applied. The member A at one end is turned up to form a right-angled hook B and at the other end has a thickened portion A², which is perforated and screw-threaded and has a countersunk portion a. A thumb-screw C, having a conical point, fits in the perforation of the member A. Near the hook end of the member A are upwardly-projecting flanges b, forming upon the upper surface of the member A a slide, in which the member A' is longitudinally movable. The member A is also provided with a slot d, which extends longitudinally between the flanges b. The member A' is shorter than the member A, and one end of the member is movable between the flanges b. The member A' is provided with a longitudinal slot d', which vertically aligns with the slot d of the member A. The members are held in position in re-

lation to each other by a thumb-screw D, which extends through the slots d and d' and is provided with a suitable head D'. The opposite end of the member A' has an upwardly-projecting right-angled flange E. The members A and A' are preferably offset at a².

When the device is to be applied to a thin wall, as shown in Fig. 4, a third member A³ is provided having an upwardly-projecting flange E', and also adapted for attachment to the member A' by the thumb-screw D.

To apply the device to a chimney F and stove-pipe H, the hook B is inserted in the chimney-flue and the flange E pressed against the opposite wall, said parts being held in this position by tightening the thumb-screw D. The outer end of the member A will thus project into the room. A collar H' is placed upon the member A and the stove-pipe H inserted in the chimney-flue through the collar and between the members A and A'. A perforation is made in the stove-pipe opposite the perforated part of the member A. The thumb-screw C is then inserted in said perforation and through the thickened portion A² of the member A and screwed into position, thus tightening the parts and firmly securing the stove-pipe. When applied to a thin wall, as shown in Fig. 4, the member A³ is placed upon the inner side of the wall F', with the flange E' abutting against the inner surface of the wall and the flange E of the member A' pressing against the outer surface of the wall. The stove-pipe is applied and secured as above described.

The device is usually applied to the upper portion of the chimney-flue; but if the inner wall of the chimney is crumbled away at that part it may be applied to any other part. As the members A and A' are capable of longitudinal adjustment, as shown, it will be readily seen that the device may be applied to a wall of any reasonable thickness, that the same size of fastener may be applied to stove or furnace pipes of different sizes, and that no special tools are needed to apply the device.

Having thus described my invention, I claim as new and desire to secure by Letters Patent—

1. In a stove-pipe clamp, the bar A, having a longitudinal slot d and an outwardly-projecting flange or hook B at its inner end and a

screw or pin receiving aperture in its outer end, a second member or bar A', extending longitudinally along the bar A and having a slot d' at its inner end registering with slot 5 d and a flange E at its outer end, a space being formed between the outer ends of the two bars or members for the introduction of a part of a stove-pipe after the device has been secured in place, and a screw or pin for locking the stove-pipe to the bar A at the apertured outer end thereof, substantially as set forth.

2. In a stove-pipe clamp, the bar A, having a longitudinal slot d, parallel side flanges b b, 15 hooked or flanged inner end B, and the boss A², having screw-threaded aperture, the second member or bar A', having a slotted inner end extending between said flanges, the adjusting-screw passed through the said two

slots, the flange E on the outer end of the 20 member A', and the thumb-screw C for said threaded boss, substantially as set forth.

3. A stove-pipe clamp consisting in a bar A, having a flanged or hooked inner end B, a longitudinal slot d, and an aperture at or 25 near its outer end, and two other superposed bars or members having longitudinally-slotted inner ends registering with the slot in bar A and having parallel flanges at their outer ends, the set-screw passing through said slots, 30 and the pin or screw to pass through the stove-pipe and the said end aperture, substantially as set forth.

FRANK A. SNOW.
